UNITED STATES PATENT OFFICE.

ERNEST E. SABIN, OF BEVERLY, MASSACHUSETTS, ASSIGNOR TO UNITED SHOE MACHINERY CORPORATION, OF PATERSON, NEW JERSEY, A CORPORATION OF NEW JERSEY.

SOLE-ROUNDING MACHINE.

Application filed February 1, 1926. Serial No. 35,250.

This invention relates to treadle devices for use in connection with starting and stopping mechanisms of various sorts and is herein shown as embodied in a sole rounding machine of the same general character as that disclosed in United States Letters Patent No. 1,048,511, granted December 31, 1912, upon application of W. G. Eaton.

In the use of rounding machines organized as set forth in said Letters Patent a blank from which a sole is to be cut is placed upon a horizontally disposed pattern while the parts of the machine are at rest and the blank is held in position by means of a presser member or clamp plate which is brought into engagement with the flat upper surface of the blank through the operation of a foot treadle and presses the blank firmly against the pattern. When the blank has been thus properly positioned and clamped, driving mechanism for causing a knife to travel around the pattern is thrown into operation by the manual shifting of a starting or shipping lever. This shipping lever is so arranged that when once thrown into an operative position it remains there while the knife travels rapidly around the pattern and upon the knife returning to its original position the driving mechanism is automatically thrown out of operation, the shipping lever is released and returns to an inoperative position, and the movement of the knife is arrested.

Thus machines constructed as just indicated require the performance of two distinct movements by the operator before the rounding operation commences: first, movement of the foot treadle to bring the presser member into contact with the blank for the purpose of clamping the blank to the pattern; and second, movement of the starting or shipping lever to throw the knife-driving mechanism into operation. Such organization of the foot treadle and the starting lever for independent actuation enables the operator to work the foot treadle to clamp the blank without danger of throwing the starting mechanism into operation until the blank is clamped in correct position, and, furthermore, either prior to or subsequently to manipulation of the starting lever, the operator may (by letting up on the foot treadle) release the presser member to free

any part of his body or clothing that inadvertently has become caught between the presser member and the blank during the positioning of the blank on the pattern. This element of safety is one of considerable importance inasmuch as the travel of the knife is rapid and injuries to an operative caused by catching his clothing beneath the presser member and being unable to escape the knife are not uncommon.

Notwithstanding the advantage of having the clamp operating treadle and the starting lever entirely independent of each other, the operative must remain at the machine throughout the travel of the knife around the pattern and hold the foot treadle depressed to prevent release of the clamping pressure and consequent slipping or skidding of the blank relatively to the pattern such as would result in inaccurate trimming of the blank. While this necessity in no way interferes with the successful operation of machines such as that disclosed in the Letters Patent above mentioned, it will be appreciated that, if it were unnecessary for the operative to hold the treadle depressed throughout the cycle of the machine, he could devote his undivided attention to the selection of a succeeding blank from his work bench and have the blank in his hand ready for positioning on the pattern immediately upon the conclusion of the rounding operation on the preceding blank, and thus the working capacity of the machine would be increased. Further, if positive mechanical means could be satisfactorily introduced to lock the presser member in fixed contact with the blank during the rounding operation the operative would be saved much labor that he would otherwise expend in holding the treadle depressed with his foot.

Sole rounding machines which contain means to control positively the presser member have been employed heretofore, but these machines have combined two starting or stopping elements such as those above referred to into a single, unitary structure, usually a foot treadle mechanism, and this structure has been so arranged that upon depression of the treadle a predetermined distance, or upon manipulation of an equivalent member, the presser member has come into clamping contact with the sole blank and

upon any further movement of the control member it has been automatically locked in the position to which it has been brought, the presser member has been automatically 5 locked in clamping contact with the blank, the starting mechanism has been simultaneously thrown into operation, and not until the completion of a cycle of operation has the driving mechanism been thrown out of 10 operation, the control member released and returned to its inoperative position and the relative movement between the parts arrested.

While such an organization provides the 15 desirable characteristic of positively locking the presser member in clamping engagement with the sole blank during the rounding operation, it provides a machine that demands exactness in its operation and calls 20 for a workman that is both skillful and experienced in the operation of the machine. Without these qualifications the likelihood of injury to the workman is considerable, owing to the necessity of the operative de- 25 pressing the treadle while at the same time positioning the blank with his hands, it being remembered that depression of the treadle past a predetermined point causes the presser member to be locked down and 30 travel of the knife about the blank to commence. And so an operative unacquainted with the machine might reasonably, although inadvertently, depress the treadle a trifle too far while positioning the blank and if at 35 that time any part of the clothing or body of the operative were caught beneath the presser member he would be helpless until the machine had completed its cycle of operation and the knife traveled completely around the pattern. Likewise, a competent 40 and skillful operator might become careless or lose his balance while operating the machine and thus effect too great a depression of the treadle and the consequent operation 45 of the machine at a time when such operation would produce a physical injury.

While the present invention, in view of the foregoing, has for an object the provision of means to maintain a presser member 50 positively in clamping engagement with a sole blank during travel of a knife around a pattern, it also contemplates the provision 55 of operating mechanism for positively controlling the presser member and its actuating mechanism that is as simple and safe as possible in its character while at the same time providing the advantage of independent control of blank positioning and clamping mechanism and sole rounding mechanism.

Accordingly, an important feature of the 65 invention consists in the combination with the rounding and sole clamping mechanism of a sole rounding machine, of means for controlling sole clamping mechanism, an in-

dependently operable member for setting the rounding mechanism in operation, and means operated by movement of said member for locking the controlling means in operative position. By this arrangement it 70 will be seen that the operative of the machine may properly position the blank upon the pattern without fear of locking the pressure applying device upon the blank until the member which sets the rounding mechanism in operation has been manually moved into an operative position.

A further important feature of the invention consists in the provision, in a sole rounding machine, of a lever for starting 80 and stopping the rounding mechanism, a member for controlling the pressure applying mechanism, means acting automatically to throw the lever into an inoperative position upon completion of a cycle of operations of the rounding mechanism, and means dependent upon movement of the lever to restore the pressure applying mechanism to an inoperative condition.

These and other important features and 90 advantages of the invention will be apparent from a reading of the following specification and inspection of the accompanying drawings, in which

Fig. 1 is a view in side elevation of the 95 machine with certain parts broken away the more clearly to show the treadle mechanism;

Fig. 2 is a plan view showing the treadle, 100 the lever, and the interconnecting mechanism;

Fig. 3 is a skeleton view in side elevation 105 of the lever for controlling the rounding mechanism, the treadle, and the mechanism for locking the treadle in a depressed position upon movement of the lever; and

Fig. 4 is a detailed view in plan showing 110 the mechanism which automatically releases the lever for controlling the rounding operation.

As hereinbefore stated the invention has 115 been shown as embodied in a sole rounding machine of the type disclosed in United States Letters Patent No. 1,048,511, and reference may be had thereto for a detailed description of the construction and operation 120 of any parts of the machine not herein fully disclosed.

Referring to the drawings, a pattern 10 is 125 stationarily mounted in the usual way upon a rotatable table or support 6. Sole rounding mechanism, not shown in the accompanying drawings but clearly illustrated in the patent already referred to, is mounted upon the table 6 and carries a knife which travels completely about the circumference of the pattern 10 to trim a sole blank 12 to the contour of the pattern.

To assist in properly positioning the blank 12 upon the pattern 10 and to hold the blank in position during the travel of the 130

knife around the pattern, a presser member or clamp plate 14 is located immediately above the pattern 10 and may be depressed into engagement with the upper surface of the blank 12. Depression of the presser member 14 is caused by the following arrangement of parts. A treadle 16 is pivoted at 18 to a part of the frame of the machine. The treadle 16 is formed in the shape of a bell-crank lever one end of which comprises the treadle proper and the opposite end of which comprises an arm 20 to which a link bar 22 is pivoted. The opposite end of the bar 22 is pivoted at 24 to a toggle mechanism comprising links 26 and 28 which are pivoted together at 30, the link 26 being also pivoted at 32 to the machine frame, while the link 28 is pivoted at 34 to an arm 36. The arm 36 is pivoted to the frame at 38 and the outward extremity of the arm 36 is provided with a cup-shaped cavity 40 within which the lower extremity of a rod 42 is seated. Depression of the treadle 16 causes straightening of the toggle 26, 28 and elevation of the arm 36 and consequently elevation of the rod 42 which is supported by the arm. The upper extremity of the rod 42 is pivoted at 44 to a fulcrum arm 46, the fulcrum being located at 48 at a point intermediate between the ends of the arm. The forward extremity of the arm 46 is connected with a crosshead 50 which supports the presser member 14. Consequently, elevation of the rod 42 causes the arm 46 to be rocked about its fulcrum point 48 to depress the pressure applying member 14, causing the latter to move toward the pattern 10. The extent of movement of the pressure applying member 14 toward the pattern and consequently the amount of pressure applied by said member to a blank upon the pattern will vary according to the extent to which the treadle 16 is depressed.

It will be seen that the operative is free to depress the treadle 16 and release it as often as he desires while positioning the blank 12 upon the pattern 10, and to assist in raising the treadle 16 from its depressed position a spring 52 may be extended between a fixed lug 54 and the arm 46. This spring provides resilient means to move the treadle to inoperative position and, in the absence of any means to lock the treadle down, it would be necessary for the operative of the machine to hold the treadle depressed to insure that the pressure applying member should press the blank 12 against the pattern 10 during the sole rounding operation.

As herein illustrated, however, provision is made for locking the treadle in depressed position and to this end a segmental ratchet member 56 is secured upon the side of the treadle arm 20. A spring-pressed pawl 58

and is pivoted at 60 to the machine frame. This pawl 58 is made in three sections, *a*, *b* and *c*, each of which may be moved downwardly independently of the remaining parts and each of which is provided with an actuating spring (Fig. 3) tending normally to produce such downward movement. The pawls *a*, *b* and *c* are arranged with their ratchet-engaging teeth staggered so as to secure a very fine adjustment of the treadle.

Locking of the treadle in depressed position is effected by movement of the pawl 58 into engagement with the ratchet 56 while the treadle occupies a depressed position and this movement of the pawl is made dependent upon the throwing into operation of the sole rounding mechanism. To this end a starting or shipping lever 62, for controlling the sole rounding mechanism, is movable between either of the two positions illustrated by full and dotted lines in Fig. 1. The starting lever 62 is provided with a depending arm 64, the lower extremity of which carries a roll 66 for engagement with a cam member 68 fixedly secured to a rock shaft 70. The rock shaft 70 is so connected with the actuating mechanism of the sole rounding mechanism that movement of the handle 62 to an operative position (illustrated by dotted lines in Fig. 1), causing a slight upward movement of the cam arm 68 and a slight rotation of the rock shaft 70, throws the actuating mechanism into operation to commence the travel of the knife around the pattern. When the operating handle 62 is moved into an operative position it is held there throughout the sole rounding operation by means of a flat surface 72 formed on a forward projection 74 of the lever moving into a locking position beneath a finger formed on a latch 76 (Fig. 4). A fixed stop 78 is carried by the machine and a spring 80, one extremity of which engages the stop 78 and the opposite extremity of which fits within a pocket 82 formed within the latch 76, tends to move the latch 76 about its pivot 84 to maintain the finger of the latch in locked engagement with the lever 62. The latch 76 for the starting lever 62 is provided with a hooked projection 86 which is to be used by the operative of the machine in manually releasing the latch and permitting the handle to return to its inoperative position.

In order to effect automatic return of the starting handle to an inoperative position upon completion of the rounding operation, and consequently throwing out of the actuating mechanism, the table 6 (Fig. 4) which rotates with the knife during its travel about the pattern is provided on its under side with a cam-shaped lug 88. In the travel of the table during the cycle of operations of the machine the lug 88 finally contacts with the latch 76 at the portion of the latch indi-

cated at 90 and swings the latch about its pivot 84 to release the starting lever 62 and to permit it to be returned to its original inoperative position. Return of the handle 5 to its inoperative position is effected by means of a spring 77 through connections with the lever 62 such as those which are shown in Fig. 1, and which correspond with similar connections fully described in the patent 10 hereinbefore referred to. The handle 62 is formed with a projection 92 (Fig. 3) which carries at its extremity a roll 94 and this roll is adapted to ride within a cut-away portion 96 formed within an enlarged upper 15 extremity 98 of a rod 100. By means of this arrangement it will be seen that movement of the handle 62 from an operative to an inoperative position causes depression of the rod 100 and movement of the handle 62 20 from an inoperative to an operative position causes elevation of the rod 100. A spring 102 encircles the rod and since the upper extremity of the spring engages with a fixed member 104 and the lower extremity 25 of the spring engages a nut 106 on the rod, it will be seen that the spring 102 constantly urges the rod downwardly. To offset the influence of the spring 102 when it is desired to maintain the rod in an elevated position, 30 a pivoted arm 108 is provided at one end with a pocket 110 in which a spring 112 is seated and the opposite end of the arm 108 carries a roll 114 which rides upon the outer surface of a cam-shaped projection 116 35 formed on the outer surface of the extremity 98 of the rod 100. By means of this arrangement the spring 112 will tend to move the roll 114 into close frictional engagement with the extremity 98 and when the projection 116 is above the roll 114 the frictional engagement will support the rod in an elevated position notwithstanding the compression of the spring 102. The lower extremity of the rod 100 engages one end of 40 a centrally pivoted link or bar 118 and the opposite end of this link or bar 118 is provided with a slot through which extends a connecting rod 120. Nuts 122 upon the upper extremity of the connecting rod 120 hold the rod within a slot formed in the link or bar 118. The lower extremity of the connecting rod 120 is connected to the pawl 58 by means of the nuts 124 so that depression of the rod 120 permits the pawl to move 45 into locking engagement with the segmental ratchet 56 and elevation of the rod 120 removes the pawl 58 from engagement with the ratchet, thus it will be seen that operation of the pawl is dependent upon movement of the connecting rod 120, the link 118, the rod 100, and consequently the lever 62 which controls the sole rounding operation. 50

In the operation of the machine, a blank 12 is placed upon the pattern 10 and by depressing the treadle 16 the presser member 14 is

brought into engagement with the blank. At this time the operative of the machine inspects the blank and the machine parts to assure himself that he is in readiness for the travel of the knife about the blank and after 70 so doing he depresses the lever 62 to throw into operation the sole rounding actuating mechanism. Depression of this handle causes upward movement of the rod 100 and permits downward movement of the rod 120 75 and engagement of the pawl 58 with the ratchet 56. At this point the treadle is locked in depressed position, the pressure applying member is locked in engagement with the blank and the actuating mechanism is operating and will continue to operate until the latch 76 has been tripped to permit the lever 62 to return to an inoperative position to throw out the actuating mechanism. As has been already pointed out, release of the latch 76 may be effected either manually or by means of the cam 88 contacting with the latch upon completion of a cycle of operations of the machine. When the latch 76 is released by either of 90 these means the lever 62 is returned to its inoperative position and the roll 92, engaging with the lower portion of the cut-away part 96 of the rod 100, causes depression of 95 that rod and consequently elevation of the rod 120 to lift the pawl 58 out of engagement with the ratchet 56 and thereafter the spring 52 acts automatically to break the toggle 26, 28 and raise the treadle 16 into 100 inoperative position. At such time the knife will have traveled completely around the blank, the pressure applying member will be lifted from the blank, and the machine will be ready to commence a new cycle of operations. 105

It will further be understood that the illustrated construction is such that the rounding mechanism may be set in motion without operating the pressure applying mechanism. Such operation may be effected 110 by moving the lever 62, which controls the rounding operation, into its depressed, operative position, without depressing the treadle 16 which controls the pressure-applying mechanism. Further, by means of 115 the projection 86 formed on the latch 76, the latter may be manually operated at any time during operation of the sole rounding mechanism to permit the lever 62 to return to its elevated inoperative position, thereby throwing out of operation the actuating mechanism. 120

Having thus described my invention, what I claim as new and desire to secure by Letters Patent of the United States is: 125

1. In a sole rounding machine, sole clamping mechanism, a member for controlling the sole clamping mechanism, rounding mechanism, an independently operable member for setting in operation the rounding 130

mechanism, and means operated upon movement of the second-named member for locking the first-named member in an operative position.

5. 2. In a sole rounding machine, sole clamping mechanism, rounding mechanism, a member for controlling the rounding mechanism, a member for controlling the clamping mechanism, and connecting mechanism 10 extending between the two members and so arranged that depression of one of the members causes the other member to be locked in a depressed position.

15 3. A machine for operating upon shoe parts having, in combination, a presser member, actuating mechanism, a lever for setting in operation the actuating mechanism, and a lever for controlling the presser member, each of said levers being arranged 20 for independent manipulation to move them into an operative position, and movement of said last-named lever into an inoperative position being dependent upon said first-named lever.

25 4. A sole rounding machine having, in combination, a presser member, a treadle mechanism for controlling the presser member, actuating mechanism, a lever operable independently of said treadle mechanism 30 for controlling the actuating mechanism, and means to lock the treadle in a depressed position, said means being dependent upon movement of the independently operable lever to effect release of the treadle member.

40 5. In a machine for peripherally contouring a boot or shoe part, a plurality of mechanisms operable simultaneously or each independently of the other, levers to set in 45 operation the mechanisms, means acting automatically to throw one of the levers into an inoperative position upon completion of a simultaneous cycle of operation of its corresponding mechanism, and means dependent upon movement of the last-named lever to restore the second mechanism to an inoperative position.

45 6. In a device of the character described, treadle mechanism adapted to apply clamp- 50 ing pressure to a shoe part, an independently operable lever adapted to stop or start operations being performed upon the shoe part, and mechanism extending between the lever and the treadle to maintain the treadle 55 in a depressed position when the lever occupies a position that allows working operations to be performed.

60 7. A sole rounding machine having, in combination, rounding mechanism, a lever for controlling the rounding mechanism, pressure applying mechanism, a treadle for controlling the pressure applying mechanism in such a manner that the amount of pressure applied varies according to the degree of depression of the treadle, and means

operated upon movement of the lever for locking the treadle in any desired degree of depression.

8. A sole rounding machine having, in combination, rounding mechanism, a lever for starting and stopping the rounding mechanism, pressure applying mechanism, a treadle for controlling the pressure applying mechanism, means operated upon movement of the lever for locking the treadle in 70 a depressed position, and means operating automatically to throw the treadle and lever to an inoperative position.

9. A sole rounding machine having, in combination, rounding mechanism, a lever for starting and stopping the rounding mechanism, pressure applying mechanism, a treadle for controlling the pressure applying mechanism, and means operated upon movement of the lever for locking the 75 treadle in a depressed position, and also for releasing the treadle from a depressed position.

10. A sole rounding machine having, in combination, rounding mechanism, a member for controlling the rounding mechanism, pressure applying mechanism, a member for controlling the pressure applying mechanism, means to lock the members in an operative position, means to throw one of the members to an inoperative position upon completion of the rounding operation, and means operated upon movement of such member to an inoperative position to release 95 the other member from an operative position.

11. A sole rounding machine having, in combination, rounding mechanism, a lever for starting and stopping the rounding mechanism, pressure applying mechanism, a treadle for controlling the pressure applying mechanism, means acting automatically 105 to throw the lever into an inoperative position upon the completion of a cycle of operations of the sole rounding mechanism, and means dependent upon movement of the lever to restore the pressure applying mechanism 110 to an inoperative position.

12. In a sole rounding machine, a presser member, a treadle, toggle mechanism extending between the presser member and the treadle, rounding mechanism, a lever, mounted independently of the treadle, for controlling the rounding mechanism, and connections extending between the lever and the treadle to cause the treadle to be locked 120 in a depressed position upon movement of the lever to an operative position.

13. A sole rounding machine having, in combination, rounding means, a starting lever, a pressure applying member, a treadle mechanism arranged to operate a toggle to cause depression of the pressure applying member, and means rendered operative by actuation of the starting lever for locking 125 130

the treadle in any desired degree of depression of said member.

14. A sole rounding machine having, in combination, a pressure applying member, a treadle mechanism for operating the pressure applying member, a segmental ratchet fixedly secured to the treadle, and a pawl having a plurality of teeth in staggered relation for engagement with the ratchet to lock the treadle in a depressed position.

15. A sole rounding machine having, in combination, a pressure applying member, a treadle, means operated by the treadle for causing depression of the pressure applying member, a spring actuated pawl tending to lock the treadle in a depressed position, a lever normally free to move into a position for actuating the rounding mechanism, and linkage extending between the lever and the pawl and so arranged that movement of the pawl into locking engagement with the treadle is dependent upon movement of the lever to an operative position.

16. A sole rounding machine having, in combination, pressure applying mechanism, a treadle for operating the pressure applying mechanism, means to lock the treadle in an operative position, rounding mechanism,

a lever normally free to move into a position for controlling the rounding mechanism, and resilient means to effect release of the treadle member, said resilient means being dependent for operation upon movement of the lever to an inoperative position.

17. A sole rounding machine having, in combination, rounding mechanism, a lever for controlling the rounding mechanism, pressure applying mechanism, a treadle for controlling the pressure applying mechanism, a pawl to lock the treadle in an operative position, a pivotal link interposed between the lever and the treadle, a rod located at one end of the link and adapted to cause pivotal movement of the link upon movement of the lever to an operative or inoperative position, and a connecting rod extending between the opposite end of the link and the pawl to cause the pawl to lock the treadle in a depressed position upon movement of the lever to an operative position.

In testimony whereof I have signed my name to this specification.

ERNEST E. SABIN.
